UNITED STATES PATENT OFFICE.

CASIMIR ZEGLEN, OF CLEVELAND, OHIO.

TIRE FABRIC.

1,385,311.

Specification of Letters Patent. Patented Mar. 30, 1920.

Application filed March 8, 1917. Serial No. 153,231.

To all whom it may concern:

Be it known that I, CASIMIR ZEGLEN, a citizen of the United States, residing at Cleveland, in the county of Cuyahoga and State of Ohio, have invented a certain new and useful Improvement in Tire Fabrics, of which the following is a full, clear, and exact description.

This invention relates to improvements in multi-ply woven fabric strips of the general character which is shown in my prior Patents, No. 604,870, granted May 31, 1898, No. 876,616, granted Jan. 14, 1908, and No. 977,357, granted Nov. 29, 1910.

The primary object of this invention is to produce a fabric strip of such form that when it is cut on the bias into short sections, these sections may be lapped and secured together to make a bias strip of indefinite length, which is of substantially the same thickness at all places; or, in other words, so that the joints produced by overlapping and joining the two overlapping edges shall be no thicker than the remainder of the strip.

The invention consists in the fabric strip which is shown in the accompanying drawings, hereinafter described, and pointed out definitely in the appended claims.

My improved fabric is illustrated in the accompanying sheet of drawings, wherein Figure 1 shows cross-sectional fragmentary parts of my improved fabric including the body and edge portions thereof; Fig. 2 is a plan view on a reduced scale of the fabric; Fig. 3 is a sectional view substantially along the line 3-3 of Fig. 2, looking in the direction indicated by the arrows; Fig. 4 is an enlarged cross-sectional view illustrating especially the disposition and length of the weft threads; Fig. 5 illustrates a length of fabric suitable for use in making tires, and illustrating the manner in which bias cut sections are united with their edge portions overlapping; and Fig. 6 is an enlarged fragmentary sectional view illustrating the manner in which the edge portions of the contiguous pieces are overlapped.

Referring to the parts by reference characters, A represents the central body portion of the fabric; and B, B', represent respectively the two integral edge portions of said fabric. The combined thickness of the two edge portions is equal to the thickness of the central body portion A. This result is due to the fact that in the body portion

the number of layers of weft threads 10 is equal to the sum of the layers of weft threads 10 in both the edge portions B and B'.

The thin edge portion B is so disposed that its top surface is flush with the top surface of the central body portion of the fabric, while the thin edge portion B' is so disposed that its bottom surface is flush with the bottom surface of the central body portion.

These results are attained by having a certain number of the top layers of the weft threads 10 go back and forth across the fabric from the left edge 12 of the body portion to the right edge of the right edge portion designated B (see Fig. 4), and by having the remainder of the weft threads 10 go back and forth from the right edge 13 of the body portion to the left edge of the left edge portion designated B'.

Warp threads 15 extend from one edge to the other of the fabric strip, and are interlaced with the layers of weft threads by reason of the fact that they extend in diagonal directions back and forth from the top to the bottom surface of the fabric. The warp threads 15 are divisible into groups each of which contains a plurality of threads, for example, if the body portion of the fabric is eight-ply thick, as shown in the drawings, that is to say, if it has eight layers of weft threads running back and forth across it, there should be nine warp threads in each group in the body portion A of the fabric.

And if each of the edge portions B, B' is four-ply thick there should be five warp threads in each group of warp threads which are in these edge portions. As with the body portion so with the edge portions, the warp threads extend diagonally up and down from the top to the bottom of the fabric and thereby are interlaced with the several layers of weft threads.

Fabric strips as above described may be made of any width, the edge portions may be of any desired width, and the fabric may be made of indefinite length. When such a strip is completed the vertical transverse section thereof will have substantially the outline shown in Fig. 3. If such a strip be now cut on the bias into sections as indicated in Fig. 5, the sides of the strip will become the ends of these sections. These ends may be now overlapped, that is to say, the edge portion B may be superimposed

upon the edge section B', and the combined thickness of these overlapped edge portions will be equal to the thickness of the body. These overlapped portions B, B', may be secured together by stitching or in any other way desired, and the result will be a bias cut strip of multi-ply fabric which is particularly useful in the manufacture of pneumatic tire casings. For this use, however, it is necessary that the threads or yarns of which the fabric is composed shall be rubberized. This may be accomplished in various ways well understood in the art, as for example, it may be dipped into a solution of rubber. Or the threads of which the fabric is woven may be rubberized before they are woven into the fabric, although to do this involves as I believe the employment of an invention which I propose to make the subject matter of another application.

Having described my invention, I claim:

1. A woven multi-ply fabric strip comprising a longitudinal extended body portion and two longitudinal extended edge portions of which one edge portion has its upper surface flush with the upper surface of said body portion and the other edge portion has its bottom surface flush with the bottom surface of the said body portion, said fabric strip consisting of warp threads which are interlaced with the weft threads and extend up and down from the top to the bottom of said fabric, and a plurality of layers of weft threads with which said warp threads are interlaced, the upper layers of said weft threads extending from the mar-

ginal edge of one edge portion to the opposite edge of the body portion, and the lower layers of said weft threads extending from the marginal edge of the other edge portion to the opposite edge of the body portion.

2. A woven multi-ply fabric strip comprising a longitudinal extended body portion and two integral longitudinal extended edge portions of equal width and of such thickness that when superimposed one upon the other their combined thickness will equal the thickness of the adjacent part of the body portion, one of said edge portions having its upper surface flush with the upper surface of the body portion, and the other edge portion having its bottom surface flush with the bottom surface of the body portion.

3. A woven multi-ply fabric formed of superimposed layers of weft threads and warp threads which are interlaced through the weft threads from the top to the bottom of said fabric, said fabric comprising a longitudinally extended body portion and two integral longitudinally extended edge portions of equal width and of such thickness that their combined thickness equals the thickness of the body portion, one edge portion having its top surface flush with the top surface of the body portion and the other edge portion having its bottom surface flush with the bottom surface of the said body portion.

In testimony whereof I hereunto affix my signature.

CASIMIR ZEGLEN.
